UNITED STATES PATENT OFFICE.

FREDERICK HENRY PAINE, OF PARIS, FRANCE, ASSIGNOR TO THE HOTCHKISS
ORDNANCE COMPANY, LIMITED, OF LONDON, ENGLAND.

SPEED-REGULATING MECHANISM FOR TORPEDOES AND OTHER VESSELS.

SPECIFICATION forming part of Letters Patent No. 478,814, dated July 12, 1892.

Application filed March 26, 1892. Serial No. 426,595. (No model.)

To all whom it may concern:

Be it known that I, FREDERICK HENRY PAINE, a citizen of the United States, residing at Paris, in the Republic of France, have 5 invented new and useful Improvements in Speed-Regulating Mechanism for Torpedoes and other Vessels, of which the following is a specification.

My invention relates to speed-regulating 10 mechanism for marine torpedoes and other vessels by which any variation in the speed of rotation of the propeller-shaft automatically varies the pitch of the propeller-blades, thus equalizing the speed of the torpedo or 15 other vessel throughout its course.

For the purposes of this application I have shown my invention as applied to a self-propelling torpedo, in which the motive power is obtained from a source of energy carried by 20 the torpedo—such, for example, as the fly-wheel described and shown in Letters Patent No. 121,052, granted John A. Howell, dated November 21, 1871—to wit, a fly-wheel to which a very rapid movement of rotation is 25 imparted by any power extraneous to the torpedo; but I do not limit myself to its use with such a motor or with a marine torpedo, as the said device may be used in any motor and in all vessels in which such requirements 30 may arise.

My speed-regulating mechanism, which when used in a self-propelled torpedo is designed to counteract the gradual decrease in the speed of the torpedo due to the gradual 35 loss of energy of the motor, is located in the tail-section of the torpedo, in a chamber open to the passage of the water, part of its mechanism being exterior to the torpedo-shell. It consists, essentially, of a moving frame, called 40 the "pitch-frame," connected with the propeller-blades, which are revolubly mounted in their hubs in such wise that a movement of the frame varies the pitch of the propeller-blades. The frame is actuated by a stud en- 45 gaging in a cam-groove of a cam-plate, the gear of which is automatically thrown into engagement with the propeller-shaft on the torpedo striking the water. The angle of the cam-groove is so proportioned to the decreas- 50 ing speed of revolution of the propeller-shaft that the pitch-frame in following the groove

proportionally increases the pitch of the propeller-blades, and thus maintains the original speed of the torpedo.

In the accompanying drawings, which illustrate my invention, Figure 1 is a vertical longitudinal section of the tail of a torpedo on the line 1 1 of Fig. 2. Fig. 2 is a horizontal longitudinal section of the same on the line 2 2 of Fig. 1, and Fig. 3 is a modification of a 60 revolvably pivoted propeller-blade adapted to be used with the speed-regulating mechanism.

A A are the propeller-shafts.

A' is a worm loosely mounted upon one of the shafts and having clutch-jogs a' at one 65 end.

A² is a clutch-collar mounted on a feather a² on the propeller-shaft A and turning with the latter, but having a longitudinal motion on the feather, so as to be thrown in and out 70 of engagement with the clutch on the worm A'.

A³ is a trigger with an enlarged disk-shaped head, mounted in suitable bearings on the horizontal fin and having an eccentric-shank a³, which works in a squared face collar a⁴ in 75 a groove a⁵ on the clutch-collar A², and a second arm a⁶, having a post a⁷, which fits in a socket in the worm A', preventing the latter from turning when the trigger is held forward by the spring A⁸ on its shank. 80

a is a spring-catch to hold the trigger when thrown back.

B is a cam-gear having a removable cam-plate B² with a cam-groove b, and is operated by the worm A' through the gears B' B'. 85

C is the horizontally-moving pitch-frame, sliding in suitable bearings c c, secured to the tail-section and having a stud C', which engages with the eccentric cam-groove b of the cam B². Rods C²C², extending from the pitch-frame C, are provided at their outer extremities with a pitch-fork c', having studs c², which engage with grooves c³ in the cam-collars C³, which are mounted and slide longitudinally on feathers c⁴ on the propeller-shafts 90 A A. The cam-collars C³, which have flat sides, one for each of the propeller-blades D, are connected to the latter by the blade-lever C⁴, one end of which has a post c⁵ traveling in a transverse groove c⁶ in the cam-collar 10 side, while the other end is securely fastened into the base of the propeller-blade D. The

latter, which are screw-threaded at the base *d*, screw into their seats *d'* in the hub *D'*, so that each blade is free to turn about its pitch-axis according as the blade-levers *C⁴* are moved by the cam-collar grooves *c⁶*. The hub *D'* is cut out to allow for the angular throw of the blade-levers *C⁴*, as shown at *d²*.

The operation of my invention is as follows: When the torpedo is placed in the tube ready for launching, the trigger *A³* is held forward by its spring *A⁴* and all of the mechanism is in the position shown in Figs. 1 and 2, with the worm *A'* disconnected from the clutch-collar *A²*, and therefore unaffected by the revolution of the propeller-shaft. The cam-gear *B* and pitch-frame *C* are at rest and the propeller-blades *D* turned to their set pitch. When the torpedo enters the water, the trigger *A³* is thrown back by the impact of the disk-head on the water and the trigger catches in the spring-catch *a*. The turning of the trigger withdraws its arm *a⁶* from the socket in the worm *A'* and simultaneously its eccentric-shank *a³* throws forward the clutch-collar *A²* into engagement with the worm *A*. This in turn sets the gear *B B'* in operation, and the pitch-frame *C*, being conducted slowly back by the progress of its stud *C'* in the cam-groove *b* of the cam-gear *B*, pushes the revolving cam-collars *C³* toward the propeller-hubs *D'*, thereby moving the blade-arms *C⁴* and turning the blades *D* to a higher pitch as the speed of the propeller-shaft decreases. This movement can also be given by drawing the cam-collars *C³* forward if the angle of the grooves *c⁶* in the cam-collar is reversed and if the cam-groove *b* of the cam-plate *B²* throws in toward the center from the periphery instead of from the center out, as shown in the drawings. The augmentation or variation of the pitch depends upon the varying angle or sinuosity in the cam-groove *b* in the cam-plate *B²* to the transverse line of the pitch-frame *C* and also to the angle of the grooves *c⁶* in the cam-collars *C³* to the blade-levers *C⁴*. The propeller-blades *D* are formed to a certain pitch, and when turned on their vertical axis the new pitch varies at each radius from the hub-center to the tip. When turned to a lower pitch than that for which formed, the pitch increases more at the tips than at the roots, which within limits is considered a favorable condition, many propeller-blades being formed in this way. When turned to a higher pitch than that for which formed, the reverse variation occurs, which is not considered a favorable condition, but may be utilized in certain cases for equalizing speed or expending superfluous power. A variable-pitch propeller should therefore be formed for nearly the highest pitch for which it is to be used, and is then an effective screw-propeller in addition to its usefulness in varying or equalizing speed. It is evident that by merely setting the cam-gear at different points in respect to the pitch-frame before the run the speed can be varied,

(for a given amount of power,) so that a shorter run at a higher speed would result, or a longer run at a slower speed with the same amount of power; also, that by replacing the equalizing cam-plate *B²* with another having a special groove throwing out from the center or from the periphery toward the center at any point the speed can be automatically varied during the run for certain useful objects. For instance, in discharging torpedoes ahead from bow-launching tubes from vessels at high speed there is danger of overrunning the torpedoes before the latter gather their way, and in this case the cam-groove could be made to give a speed sufficiently greater than the average speed (for a short distance) to avoid such danger, and then to curve in so as to produce an equalizing speed for the remainder of the course; or it might be desirable to run a torpedo or boat at a moderate rate of speed for the greater part of its run and then to cause it to take up an extremely high velocity as a striking force against nets or other obstructions.

The parts of the variable-pitch mechanism outside the tail-cone, excepting the trigger, are screened from passing water by thin metal screens to guide the water to the propellers.

I do not limit myself to the use of the variable-pitch mechanism or the variable-pitch propellers in marine torpedoes alone, as it is evident that the general system can be applied to any boat in such manner that all operations of backing or slowing on one or more propellers or engines can be done from the pilot-house for maneuvering purposes.

In place of screwing in the blades *D*, as shown in Fig. 1, they may be mounted with a universal joint, as shown in Fig. 3.

I do not limit myself to the particular means for pivoting the revoluble propeller-blades, as the same may be greatly varied, provided that the blades shall always be capable of varying their relation to the axis of the propeller-hub.

While I have shown the trigger *A³* as held by a catch *a*, it is evident that the catch may be omitted and the tension of the spring *A⁴* so adjusted as to yield only at a certain rate of speed through the water, and to release the clutch-collar from the worm at a lower speed. Neither do I limit myself to any particular form of trigger, as it also may be varied in a great number of ways without departing from the spirit of my invention.

In addition to controlling the speed of the torpedo by varying the pitch of the propeller-blades the pitch-frame *C* may be utilized for various purposes—such, for example, as holding the rudders at any desired angle for any given time, (measured by the revolution of the propeller-shaft and for controlling a pendulum-immobilizing attachment,) as shown in my application, Serial No. 426,594, filed March 26, 1892.

Having thus described my invention, what

I claim as new, and desire to secure by Letters Patent, is—

1. The combination, with twin propellers having blades pivotally mounted in the propeller-hub, of a pitch-regulating device for rotating the blades about a pitch-varying axis, suitable lever connections between it and the blades of each propeller, and driving mechanism between the pitch-regulating device and the shaft of one of the propellers, whereby the pitch of the blades of each propeller is automatically and simultaneously controlled, substantially as described.

2. The combination, with a propeller-shaft and a propeller having blades pivotally mounted in the propeller-hub, of a pitch-regulating device for rotating the blades about a pitch-varying axis and mechanism driven by the propeller-shaft automatically controlling the pitch-regulating device, substantially as described.

3. The combination, with a propeller-shaft and a propeller having blades pivotally mounted in the propeller-hub, of a pitch-regulating device for rotating the blades about a pitch-varying axis, mechanism driven by the propeller-shaft to control the pitch-regulating device, and a device for connecting and disconnecting the driving mechanism and the propeller-shaft, substantially as described.

4. The combination, with a propeller-shaft and a propeller having blades pivotally mounted in the propeller-hub, of a pitch-regulating device for rotating the blades about a pitch-varying axis, mechanism driven by the propeller-shaft to control the pitch-regulating device, and a device automatically operated by the impact of the water for throwing the driving mechanism into and out of gear with the shaft, substantially as described.

5. The combination, with a propeller-shaft and a propeller having blades pivotally mounted in the propeller-hub, of a collar revolving with and sliding longitudinally on the propeller-shaft, lever connections between the collar and the blades, and automatic mechanism between the collar and the propeller-shaft to slide the collar along the shaft, whereby the blades are rotated about a pitch-varying axis, substantially as described.

6. The combination, with a propeller-shaft and a propeller having blades pivotally mounted in the propeller-hub, of a collar revolving with and sliding longitudinally on the propeller-shaft, lever connections between the collar and the blades, a sliding pitch-frame, transmitting connections between the pitch-frame and the collar, a cam device engaging with the sliding pitch-frame to govern its rate of motion, and driving mechanism between the propeller-shaft and cam device, whereby the pitch of the propeller-blades is automatically varied, substantially as described.

7. The combination, with a propeller-shaft and a propeller having blades pivotally mounted in the propeller-hub, of a sliding pitch-

frame, suitable transmitting connections between the pitch-frame and the propeller-blades, a cam device engaging with the pitch-frame to govern its rate of motion, and driving mechanism between the propeller-shaft and the cam device, whereby the pitch of the blades is automatically varied, substantially as described.

8. The combination, with a propeller-shaft and a propeller having blades pivotally mounted in the propeller-hub, of a sliding pitch-frame, suitable transmitting connections between the pitch-frame and the propeller-blades, a cam device engaging with the pitch-frame to govern its rate of motion, driving mechanism between the propeller-shaft and the cam device, and an automatic device released by the pressure of the water to throw the shaft and driving mechanism into and out of gear, substantially as described.

9. The combination, with a propeller-shaft, of a sliding frame, a cam device engaging with the sliding frame, and driving mechanism between the propeller-shaft and the cam device, whereby the cam device automatically controls the rate of motion of the frame, substantially as set forth.

10. The combination of the propeller-hub D', having the screw-threaded recesses d', the blades D, having the threaded bases d, the propeller-shaft A, the cam-collar C³, having flat sides opposite each blade and sliding longitudinally on the feather c⁴ of the shaft A, and the lever-arms C⁴, secured at one end to the base of the blades and having at the other end the posts c⁵, engaging in grooves c⁶ in the cam-collar sides, substantially as set forth.

11. The combination of the propeller-hub D', having the screw-threaded recesses d', the blades D, having the threaded bases d, the propeller-shaft A, having the feather c⁴, the cam-collar C³, sliding longitudinally thereon and having flat sides grooved at c⁶, the lever-arms C⁴, secured to the blades and having the posts c⁵ traveling in the cam-collar grooves, the longitudinally-sliding pitch-frame C, the arms C², connected to the pitch-frame and having the pitchforks c' seated in the groove c⁸ of the cam-collars C³, the cam-gear B, having the sinuous cam-groove b, engaging with the stud C' on the pitch-frame, the driving-gear B' B', meshing with the cam-gear, the worm A', loosely mounted on the propeller-shaft and meshing with the driving-gear, the clutch-collar A², mounted on shaft A and sliding longitudinally on the feather a², and the trigger A³, having an enlarged head and eccentric-shank a³, engaging in the groove a⁵ of the clutch-collar, and an arm a⁶ with post a⁷, engaging with the worm and spring A⁴, substantially as described.

12. The combination, with the propeller-shaft A, of the worm A', loosely mounted thereon, the clutch-collar A², sliding on the feather a² on the shaft A, the trigger a³, hav-

ing an enlarged head, an eccentric-shank a^3 ,
engaging in the groove a^5 of the clutch-collar,
an arm a^6 with a post a^7 engaging the worm
and spring A^1 , whereby the clutch-collar is
5 thrown into and out of engagement with the
worm by the impact of the water on the trig-
ger-head, as described.

In testimony whereof I have hereunto set
my hand in the presence of two subscribing
witnesses.
